Primary Examiner — Lauren D McVey

(57) **CLAIM**

The ornamental design for a budget binder, as shown and described.

DESCRIPTION

FIG. 1 is a perspective view of a budget binder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The short thin evenly spaced broken lines immediately adjacent to the shaded areas depict the bounds of the claimed design, while all other broken lines are directed to environment. The long thick evenly spaced broken lines depict stitching that form no part of the claimed design.

1 Claim, 8 Drawing Sheets
